RAILWAY TRAFFIC CONTROLLING APPARATUS

Charles B. Shields, Penn Township, Allegheny County, Pa., assignor to The Union Switch & Signal Company, Swissvale, Pa., a corporation of Pennsylvania

Application May 27, 1946, Serial No. 672,395

12 Claims. (Cl. 246—33)

1

My invention relates to railway traffic controlling apparatus for governing the movement of traffic over stretches of single track over which traffic moves in two directions. More particularly, my invention relates to an improved absolute permissive block signaling system employing cascade connected reversible track circuits of the continuous code type, for use in a centralized traffic control system in which the traffic direction is set up and the head block signals are cleared by manual control from a central office by means of an intermittently operated communication system, while the intermediate signals, which are controlled solely by the track circuits, are cleared automatically in one direction or the other in accordance with the direction of energization of the track circuit system.

In an absolute permissive block signaling system, such as is herein disclosed, directional stick relays are provided in connection with the intermediate signals, each of which is normally arranged to become energized when a train passes the associated signal at clear or caution, and when energized prepares a circuit for energizing the next signal in the rear, governing traffic movements in the same direction, to permit that signal to indicate caution as soon as the block section in advance is vacated by a train.

The principal object of my invention is the provision of improved means for controlling these directional stick relays by the track relays of a coded track circuit system, so that each directional stick relay becomes energized when the code operation of the associated track relay ceases due to a train entering the corresponding track section in the established direction, but not when the operation of the track relay is discontinued due to an opposing train overrunning a head block signal nor when the track circuit system is manually deenergized in preparation for reversing the direction of traffic.

A feature of my invention is the provision of means for terminating the supply of coded track circuit current to the rails of each section having a track relay which controls a directional stick relay, by a period of steady energization during which a code detector relay governing the signal is released without operating the directional stick relay, whereby the directional stick relay is selectively energized or not, depending upon whether the track relay remains released when its periodic operation ceases, as is the case when the controlling track section is occupied, or whether it remains steadily energized for a time, as is the case if the supply of coded current to the track rails

2

is interrupted when the controlling track section is not occupied.

Other objects and features of my invention will be pointed out as the description proceeds.

5 I shall describe one form of apparatus embodying my invention and shall then point out the novel features thereof in claims.

Referring to the accompanying drawings, Figs. 1A, 1B, 1C and 1D, placed side by side in the order listed illustrate the track plan and wayside circuits for a typical single track block embodying the apparatus of my invention. The block shown includes three sections, over which opposing traffic movements are governed by the entering head block signals 2RA and 2RB, Fig. 1A, and by the similar signals 4LA and 4LB of Fig. 1D. Figs. 2 and 3 show two forms of cut section apparatus which may be interposed between any two of the drawings illustrating the single track block. It is to be understood that such apparatus is required for any block section the length of which exceeds the permissible length of a single coded track circuit. Fig. 4 shows circuits for the control of an outlying hand throw track switch W, this view being arranged to be interposed between Figs. 1B and 1C. Figs. 1A and 1D also show different portions of the circuits for the leaving signals 2LA and 2LB and the similar signals 4RA and 4RB. These signals also constitute the entering signals for a typical block comprising the main track of the double track stretch including the passing track, the circuits for which may be viewed in their entirety by placing Fig. 1A at the right of Fig. 1D.

35 Similar reference characters refer to similar parts in each of the views.

To simplify the circuit drawings, only the terminals of the local sources of current for energizing the relays are shown, these being designated by the reference characters B and C, respectively. Each track switch and railway signal is identified by a number identifying its location, the signal designations also including the suffix L or R to indicate the corresponding direction of traffic movements to the left or right, respectively. Each relay is identified by a characteristic letter or combination of letters, prefixed by the designation of the switch or signal with which it is associated. The track relays TR in each of the views, and also the approach relays AR of Figs. 1B and 1C by which the lamps of the intermediate signals are caused to be lighted upon the approach of a train, are code following relays of the biased polar type, such as shown for example in Letters Patent of the United States No. 2,057,605,

issued October 13, 1936 to Herman G. Blosser. The polarity responsive feature is designated by an arrow on the relay winding, and it is to be understood that each such relay is normally biased to its released position and assumes its energized position only when current flows from the plus terminal of the track battery through its winding in the direction of the arrow. Relay 6LTR of Fig. 1B, for example, is picked up by current received over the track rails only when the plus terminal of the source TB at the left-hand end of the section, shown in Fig. 1A, is connected to the lower track rail, and is non-responsive to current supplied through its winding to the track rails by the battery TB at the right-hand end of the section. Relay 6RAR, which is connected through a resistor across the terminals of relay 6LTR when the contacts of relay 6LCT are closed, responds to the current supplied by the battery TB at the same location, but only when this is increased by the presence of a train within the approach lighting limits for signal 6R. The periodically operating contacts of the code following relays are distinguished from those of other quick acting relays by horizontal dotted lines indicating their closed positions. The contacts of slow acting relays are identified in the conventional manner by vertical arrows thereon. It is to be understood that the slow acting relays having condensers associated therewith have release periods of about five seconds.

Each of the block signals as shown, is of the well-known searchlight type having a three-position mechanism identified by the reference character G prefixed by the designation of the corresponding signal. It is to be understood that the signal mechanisms, and also the polar neutral relays 2LHD and 4RHD are so polarized that they close their left-hand contacts when terminal B is applied to the left-hand terminals of their windings. To simplify the drawings the lighting circuits for the head block signals of Figs. 1A and 1D are not shown, since suitable circuits are well known.

Inasmuch as my invention relates to wayside apparatus, the centralized traffic control system by means of which the direction of energization of the signal circuits and the clearing of the entering signals is made subject to manual control from a central office is not shown herein, but it is to be understood that this is preferably a remote control system of the code type such as that disclosed in Letters Patent of the United States No. 2,229,249, issued January 21, 1941, to Lloyd V. Lewis, for Remote Control Systems, or more particularly, is a modification thereof described in a publication entitled "Centralized Traffic Control System—Time Code Scheme, Manual No. 506-A," published by the Union Switch and Signal Co., Swissvale, Pennsylvania. For an understanding of my invention, it will suffice to point out that the remote control system has a field station at the end of each block which is connected with a control office by a line circuit over which codes are transmitted in either direction for selective communication between the office and the different stations, one at a time. The control codes transmitted to the stations serve to operate a group of control relays of the stick polar type, in accordance with the positions of control levers at the office. Four such control relays are shown herein at each station, and as shown in Fig. 1A these comprise a traffic relay for each direction, such as relay 2LFS or 2RFS, which govern the direction of traffic movements in the blocks ex-

tending in opposite directions from the station, by cooperation with similar relays 4RFS and 4LFS at the opposite ends of the respective blocks, shown in Fig. 1D, and also include two signal control relays, such as the relays 2RHS and 2LHS or 4RHS and 4LHS, by which the clearing of the correspondingly designated entering signals is made subject to manual control from the office. Each traffic relay LFS or RFS when in its normal position as shown, with its left-hand contacts closed, designates its location as the entrance end of its block, in which position the traffic relay enables the adjacent entering head block signal to be cleared under proper conditions, in response to the reversal of the associated signal control relay 2RHS or 2LHS. Each traffic relay when reversed, with its right-hand contacts closed, designates its location as the exit end of the block. In this position the traffic relay supplies energy to the signal circuits for the block to enable the signals which govern traffic movements toward its location to be cleared.

The trackway system includes continuous track circuits for all main track. The detector sections at the ends of the block each have a conventional track circuit including a track relay, such as relay 1TR, which is normally energized by a track battery as shown. The remaining track circuits of the single track block are of the reversible coded type, connected in cascade when the block includes two or more sections, and provide means for controlling the signals for both directions to provide three indications and for also indicating at either end whether or not the block is occupied, without line wires. Since the block which includes the main track of the double track portion is relatively short, this is more conveniently controlled by the provision of a conventional track circuit having a normally energized track relay 6TR which controls the signals by means of a two-wire reversible line circuit system comprising the line wires 21 and 22, as shown, this arrangement corresponding to that disclosed in an application for Letters Patent of the United States, Serial No. 539,619, filed June 10, 1944, by John C. Law, for Railway Traffic Controlling Apparatus, now Patent No. 2,404,303, issued July 16, 1946.

The present invention relates more particularly to the coded track circuit apparatus, and is an improvement upon that disclosed in an application for Letters Patent of the United States, Serial No. 596,470, filed May 29, 1945, by Henry S. Young, for Railway Traffic Controlling Apparatus. In the system of this Young application, the coded track circuits are normally de energized and are set up by manual control by reversing the traffic relay at the exit end of the block for the desired direction of traffic movement, and then reversing the signal control relay for the entering signal at the other end of the block. This system is also so arranged that when a train vacates the block and an indication of that fact has been transmitted to the office, the operated traffic relay is restored automatically to normal, and the wayside circuits thereby restored to their normal deenergized condition. This mode of operation may be employed in connection with the track circuits of my invention, or they may be left energized until a reversal of the traffic direction is required to provide a normally energized system. It is also to be understood that the remote control system preferably includes means for preventing the op-

eration of the traffic and signal control relays except under the proper traffic conditions, so that a signal cannot be put to stop by the operation of any lever other than its control lever, one arrangement suitable for this purpose being disclosed in the above mentioned Young application.

In the coded track circuit system as disclosed herein, the coded currents are generated by code transmitters of the pendulum type designated 180CT, 120CT and 75CT, which when energized operate their contacts periodically at a rate of 180, 120 or 75 times per minute, respectively, to periodically operate the transmitter relay such as relay 2RCT, by which the coded current of the selected frequency is supplied to the track rails.

Each code following track relay, such as relay 2RTR, is provided with a slow release, front contact repeater, such as the relay 2RTF, which remains picked up as long as the track relay is responding to coded current. The code responsive apparatus at the different signal locations is substantially similar and its operation will be understood from a description of that of Fig. 1A, where it will be seen that the closing of front contact *a* of relay 2RTR when its code operation begins energizes relay 2RTF, and the closing of front contact *a* of relay 2RTF prepares a circuit over which a code following repeating relay 2RTP is energized each time the track relay 2RTR releases. The closing of contact *b* of relay 2RTF energizes the primary winding of a decoding transformer 2DT over contact *a* of relay 2RTP, transformer 2DT being thereby supplied with current which alternates in direction at the code rate, inducing current in its lower winding which is rectified by the operation of contact *b* of relay 2RTP to energize a slow acting code detector relay 2RH, which thus responds selectively to the code operation of relay 2RTR. Transformer 2DT also supplies code frequency currents to resonant decoding units 120DU and 180DU, which it is to be understood are of the type disclosed in Letters Patent of the United States No. 1,773,472, issued August 19, 1930, to Paul N. Bossart, for Railway Traffic Controlling Apparatus, whereby the decoding relays 2RD and 2RK are selectively energized when the code operation of relay 2RTR is at the rate of 120 or 180 times per minute, respectively.

The circuits for controlling the track switches 1W and 3W which lead to the passing tracks at the ends of the single track block have been omitted in order to simplify the drawings, and it will be understood that when switch 1W is locked in its normal position as shown, a normal switch repeating relay 1NWP is energized, and when switch 1W is locked in reverse, a reverse switch repeating relay 1RWP is energized, over the contacts N and R respectively, of a circuit controller actuated by switch 1W. These relays serve to select the signal mechanism 2RAG or 2RBG for energization, in accordance with the position of the track switch, the selected signal indicating caution when the code detector relay 2RH is energized, or indicating proceed in the event relay 2RD or 2RK is also energized. When either signal mechanism has been energized in the manner hereinafter described, a normally energized indicating relay 2RGP is released by the opening of contacts controlled by the signal mechanism, and relay 2RGP opens a contact in the circuit for an approach locking stick relay 2RAS associated therewith. Relay

2RAS provides the usual time and approach locking required in connection with the operation of signals 2RA and 2RB, having a front contact *d* in the circuit for the transmitter relay 2RTC and a front contact *c* in the circuits for the mechanisms 2LAG and 2LBG for signals 2LA and 2LB governing opposing traffic movements, and a back contact *c* in the circuits for the mechanisms for the associated signals 2RA and 2RB. Relay 2RAS is released to complete the mechanism circuit to permit the selected signal to be cleared by the provision of a block repeating relay 2RBP which becomes energized in response to the reversal of the signal control relay 2RHS but only if the required traffic direction is established and a route is available.

The circuits for controlling the opposing signals 2LA and 2LB are generally similar to those for signals 2RA and 2RB except that they are controlled by the polar neutral relay 2LHD instead of by code responsive relays, and mechanism 2LBG is operable only to its caution position, in view of the fact that movements into the side track are limited to slow speed.

25 The operation of the system is generally similar for both directions of traffic movement and the circuits of Fig. 1D, therefore, are similar to those of Fig. 1A, except that they are oppositely directed. Likewise the apparatus at the two intermediate signal locations of Figs. 1B and 1C is similar, but oppositely directed. In these views, but one set of decoding apparatus is used, this being arranged for either direction of operation depending upon which of the track relays is operated, and in addition, a pair of directional stick relays, such as the relays 2RS and 2LS, is provided for controlling the energization of the track circuit system as required for the following train movements in either direction.

30 40 The mode of operation of the coded track circuit system will now be described under different assumed conditions by tracing the circuits in detail, starting with the apparatus in its normal deenergized condition, as shown, and assuming first that the central office operator reverses the traffic relay 2RFS, Fig. 1A, and also reverses the signal control relay 4LHS, Fig. 1D, for a train movement from right to left. Since signal 2LA is at stop, its repeating relay 2LAPC is released, 45 in which case the reversal of relay 2RFS completes circuits from terminal B at its contact *a* over back contact *a* of relay 2LAPC to set the code transmitter 75CT into operation, and from terminal B at contact *b* of relay 3RFS, front contact *b* of a repeating relay 1TP of the detector track relay 1TR and front contact *b* of an approach locking relay 2RAS to pick up a relay 2RAF, which in turn energizes a slow release repeating relay 2RAFP, completing a branch of the 50 circuit just traced over back contact *b* of relay 2LAPC, contacts *a* of the code transmitter 75CT and of relays 2RAF and 2RAFP and a connector X through relay 2RTC to terminal C, whereby relay 2RCT is caused to supply current interrupted at the 75 code rate to the track rails, to which the code following track relay 6LTR of Fig. 1B responds. In Fig. 1B, relay 6LTF is energized over the circuit from terminal B at back contact *d* of a directional stick relay 6RS and 55 front contact *a* of relay 6LTR, and prepares a circuit for the code following repeating relay 6TP over back contact *a* of relay 6LTR, front contact *a* of relay 6LTF and back contact *a* of relay 6RTF through relay 6TP to terminal C, so that relay 6TP operates at the same rate as relay 2RCT.

The closing of front contact *b* of relay 6LTF supplies current over contact *a* of relay 6TP to the primary winding of the decoding transformer 6DT and also sets the associated code transmitter 180CT into operation, and the periodic operation of relay 6TP causes the code detector relay 6H to become energized over contact *b* of relay 6TP. A slow release repeating relay 6HP is energized over front contact *b* of relay 6H, and a circuit is closed from terminal B at contact *a* of relay 6H over back contact *a* of a decoding relay 6D, back contact *c* of relay 6RTF, front contact *c* of relay 6LTF through mechanism 6LG to terminal C at back contact *b* of relay 6D. Mechanism 6LG is therefore energized to condition signal 6L to indicate caution, completing a circuit from terminal B at its front contact Y over contact *b* of the code transmitter 180CT, front contact *e* of relay 6H, back contact *b* of a directional stick relay 6LS through the winding of transmitting relay 6RCT over back contact *c* of relay 6RS to terminal C at the back contacts of mechanism 6RG. Relay 6RCT therefore operates to supply current interrupted at the 180 code rate to the track rails of the section in the rear of signal 6L, to which the track relay 8LTR of Fig. 1C responds. In Fig. 1C, due to the operation of relay 8LTR at the 180 code rate, relay 8LTF becomes energized to cause relay 8LTR to operate relay 8TP at the same rate and to supply current to the decoding transformer 8DT whereby the code detector relay 8H, its repeater relay 8HP, and the decoding relay 8D are energized and mechanism 8LG is energized over the front contacts of relays 8H and 8D to condition signal 8L to indicate proceed. The code transmitter 180CT of Fig. 1C is set into operation by current supplied from terminal B at front contact *b* of relay 8LTF over back contact *b* of relay 8RTF and front contact *c* of relay 8D, and operates the transmitter relay 8RCT at the 180 code rate over the circuit from terminal B at front contact *G* of mechanism 8LG, contact *a* of the code transmitter 180CT, front contact *d* of relay 8D, front contact *f* of relay 8H, back contact *b* of a directional stick relay 8LS through the winding of relay 8RCT over back contact *c* of a directional stick relay 8RS to terminal C at the back contacts of mechanism 8RG.

Relay 8RCT therefore supplies current interrupted at the 180 code rate to the track rails of the section in the rear of signal 8L, to which the track relay 4LTR of Fig. 1D responds. In Fig. 1D, due to the operation of relay 4LTR at the 180 code rate, relay 4LTF becomes energized to cause relay 4LTR to operate relay 4LTP at the same rate and to supply current to the decoding transformer 4DT whereby the code detector relay 4LH and the decoding relay 4LK are energized.

Since the signal control relay 4LHS has been reversed by the central office operator under the conditions assumed, and since switch 3W is normal, relay 4LH energizes the block repeating relay 4LBP over the circuit from terminal B at the normal contact *b* of relay 4LFS, contact *a* of relay 4LH, the normal contact *a* of relay 4RHS, contact *b* of the detector section track relay 3TR, back contact *a* of relay 3RWP, front contact *a* of relay 3NWP, reverse contact *a* of relay 4LHS through relay 4LBP to terminal C.

Relay 4LBP when energized, releases the approach locking relay 4LAS by opening its normally closed stick circuit which extends from terminal B over back contact *a* of relay 4LBP, back contact *c* of the signal repeating relay 4LAPC and

75

front contacts *a* of relays 4LGP and 4LAS through the winding of relay 4LAS to terminal C and relay 4LAS upon releasing completes a circuit for mechanism 4LAG extending from terminal B at front contact *a* of relay 4LBP over front contact *c* of relay 4RAS, back contact *c* of a time element relay 3TER, back contact *c* of relay 4LAS, front contacts *b* of relays 4LK and 3NWP, through the winding of mechanism 4LAG and over back contact *b* of relay 3RWP, front contact *a* of relay 4LK and front contact *b* of relay 4LBP to terminal C. Signal 4LA is thereby caused to display its proceed indication and the operation of contact *G* of mechanism 4LAG causes relay 4LGP to release and relay 4LAPC to become energized.

By placing Fig. 1A at the right of Fig. 1D, it will be seen that if the traffic relay 4RFS and the signal control relay 2LHS are reversed by the operator, current will be supplied to relay 2LHD under proper traffic conditions as reflected by relay 3TR and relays 4RAS and 3TP or relay 3RWP, over the contacts *a* and *b* of relays 4LAPC and 4RFS. The line wires 21 and 22 and the normal contacts *a* and *b* of relay 2LFS to operate relay 2LHD to reverse if relay 4LAPC is released and to normal if relay 4LAPC is energized, and that the closing of the front contact *a* of relay 2LHD will complete a circuit from terminal B over contacts *a* of relays 4RHS, 1NWP and 1RWP, contact *b* of relay 1TR and over the reverse contact *a* of relay 2LHS to energize the block repeating relay 2LBP, thereby releasing relay 2LAS and energizing mechanism 2LAG, so that signal 2LA in the rear of signal 4LA will indicate caution when signal 4LA indicates stop and will indicate proceed when signal 4LA indicates caution or proceed.

The caution control circuit for mechanism 4LAG, closed when relay 2LHD is energized reverse, may be traced from terminal B at front contact *a* of relay 4LBP over front contact *c* of relay 2RAS, back contacts *c* of relays 1TER, 2LAS and 1RWP, front contact *c* of relay 1NWP, reverse contact *c* and front contact *b* of relay 2LHD, the winding of relay 2LAG, reverse contact *d* of relay 2LHD to terminal C at contact *b* of relay 2LBP. The proceed control circuit for mechanism 4LAG is similar, except that it includes the normal or left-hand contacts *d* and *c* of relay 2LHD.

The circuits as shown are arranged as required when the control limits for signal 2LA are insufficient to provide stopping distance for high speed trains, and accordingly, the control limits for signal 8L in the rear of signal 2LA are extended by energizing relay 2LAPC only when signal 2LA indicates proceed. Relay 2LAPC when energized causes the transmitter relay 2RCT to operate at the 180 code rate instead of at the 75 code rate for the control of relay 6LTR of Fig. 1B, and it follows that when signal 2LA indicates proceed relay 6H will be energized along with relay 6L to reverse the polarity of the current supplied to mechanism 6LG so that signal 6L will also indicate proceed.

The movement of a train through the single track block will now be traced, assuming that signals 2LA, 6L, 8L and 4LA have been conditioned to indicate proceed as above described.

Signal 4LA is put to stop by the release of relays 3TR and 4LBP when the train enters the detector section 3T, and it is to be understood that the signal control relay 4LHS is restored automatically to normal and an indication of the occupancy of section 3T is transmitted to the con-

trol office as described in the manual hereinbefore referred to. Relay 4LGP becomes energized, the closing of its contact *a* allowing relay 4LAS to pick up over back contact *c* of the track relay 3TR to reestablish its stick circuit.

When the train enters the first coded track circuit of the block, the operation of relay 4LTR ceases, and relays 4LTF, 4LH and 4K release. Due to the shunting effect of the wheels and axles of the train, the current supplied to the rails by relay 8RCT increases as the train approaches signal 8L until the series connected approach relay 8LAR begins to respond, thereby energizing the slow release repeating relay 8LAP, which by closing its contact *a* completes a circuit for the lamp of signal 8L to cause this signal to display its proceed indication. The closing of contact *b* of relay 8LAP decreases the value of resistance in series with relay 8LAR and thereby stabilizes its operation to prevent the flickering of the signal lamp which might otherwise occur when relay 8LAR first starts to operate, in the event the current supplied at that time is insufficient for reliable operation.

As the train passes signal 8L, the code operation of relay 8LTR ceases with the relay in its released position, deenergizing relay 8LTF, but relay 8TP is held steadily energized for a period of several seconds corresponding to the release period of relay 8LTF, during which relays 8H and 8D release. Relay 8H deenergizes relay 8HP, and for the release period of relay 8HP a circuit for the directional stick relay 8LS is completed from terminal B over front contacts *d* of relays 8LTF and 8TP, front contact *b* of relay 8HP, back contact *d* of relay 8H, the winding of relay 8LS, back contact *c* of relay 8RS to terminal C at the back contacts of mechanism 8RG. Relay 8LS picks up, completing a stick circuit including its own front contact *a* and back contact *d* of relay 8H over which relay 8LS is held picked up until relay 8H is again energized, and by closing its front contact *d*, relay 8LS sets the code transmitter 75CT into operation. The release of relay 8H also deenergizes mechanism 8LG, causing signal 8L to indicate stop, and then relay 8LTF releases to discontinue the operation of the code transmitter 180CT. Relay 8RCT continues to operate, but at the 75 code rate, being now energized over front contact *b* of relay 8LS and contact *a* of the code transmitter 75CT.

When the train vacates the section in the rear of signal 8L, relay 8LAR ceases to operate, and after several seconds relay 8LAP releases to extinguish the lamp for signal 8L. Relay 4LTR responds to the 75 code supplied to the track rails, energizing relays 4LTF and 4LH, so that, if relay 4LHS has been reversed again by the operator to enable a following train to enter the stretch, relay 4LBP picks up and mechanism 4LAG will be energized over the back contacts of relays 4LD and 4LK to cause signal 4LA to indicate caution.

As the train passes signal 6L, similar operations occur, signal 6L is restored to stop and relay 6LS becomes energized, and 75 code is supplied by relay 6RCT to the rails of the section in the rear, and when the train vacates this section, relay 6LTR responds to the 75 code to energize relays 6LTF and 6H. Relay 6LS is released by relay 6H, and relay 6LTF completes a circuit from terminal B at its front contact *b* over back contact *b* of relay 6RTF and back contact *c* of relay 6D to set the code transmitter 120CT into operation, so that relay 6RCT is op-

erated at the 120 code rate, over the branch of its circuit which includes contact *a* of the code transmitter 120CT and back contact *d* of relay 8D. Accordingly, in Fig. 1D, relay 4LD becomes energized along with relay 4H, so that if mechanism 4LAG is energized, the polarity of the current supplied thereto is reversed to change its indication from caution to proceed:

As the train passes signal 2LA, relays 1TR, 1TP and 2LBP release, restoring signal 2LA to stop. The opening of contact *b* of relay 1TP releases relays 2RAF and 2RAFP and stops the code operation of relay 2RCT so that relay 6LTR remains released after the train vacates the section in the rear of signal 2LA. Relay 2LAPC releases, setting the associated code transmitter 75CT into operation in place of transmitter 180CT. When the train vacates section 1T, relays 1TR, 1TP, 2RAF and 2RAFP are reenergized and relay 2RCT supplies 75 code to the section in the rear, the operation of relay 6LTR at that rate energizing relays 6LTF and 6H, thereby energizing mechanism 6LG to condition signal 6L to indicate caution, and releasing relay 6LS. Relay 6RCT is then caused to operate at the 180 code rate and the operation of relay 8LTR at that rate energizes relay 8D along with relay 8H, reversing the polarity supplied to mechanism 8LG to change the indication of signal 8L from caution to proceed. The code transmitter 180CT of Fig. 1C is energized over front contact *c* of relay 8D and relay 8RCT supplies 180 code to the section in the rear of signal 8L and the operation of relay 4LTR at that rate energizes relay 4LK in place of relay 4LD to maintain signal 4LA at proceed. In addition, relay 4LK completes a circuit over its contact *c* and a wire 14 by which the code communication system may be caused to light a lamp EKE at the control office, as shown diagrammatically in Fig. 1D, the lighting of which indicates to the operator that the entire block is vacant and that the traffic relay 2RFS may properly be restored to normal.

Assuming next that after the signals for the single track block have been cleared by the reversal of relay 2RFS as described, with relay 4LK energized, that the operator restores relay 2RFS to normal. This releases relay 2RAF and stops the code operation of relay 2RCT. Relay 2RAF deenergizes relay 2RAFP, and during the release period of relay 2RAFP, which is of several seconds duration, relay 2RCT is held steadily energized over the circuit from terminal B over back contact *a* of relay 2RAF, front contact *a* of relay 2RAFP, and connector X. In Fig. 1B, relay 6LTR is held energized for the same period. During this period relay 6TP remains steadily released and is then reenergized, releasing again at the end of the release period of relay 6LTF. The release of relays 6H and 6HP occurs during the first of these periods, and therefore occurs when front contact *c* of relay 6TP is open, consequently relay 6LS does not become energized when, as in this case, the code operation of the track relay is terminated by a relatively long period during which the track relay is steadily energized.

As soon as relay 6H releases, the code operation of relay 6RCT ceases and during the remainder of the period of steady energization of relay 6LTR relay 6RCT is held energized over the circuit from terminal B at contact *d* of relay 6LTF over back contact *c* of relay 6TP, back contact *e* of relay 6H and back contact *b* of relay 6LS.

The steady current supplied to the track rails by relay 6RCT holds the track relay 8LTR steadily energized for a prolonged interval with the same effect as when relay 6LTR is steadily energized, that is, relay 8LTR is held energized following the termination of its code operation for a time sufficient to cause the release of relays 8H and 8HP without energizing relay 8LS.

Since the track section controlled by relay 8RCT does not have a directional stick relay at its entrance end, it is not necessary to terminate the code operation of that relay by a period of steady energization. This, however, would be provided in the event the block included an additional intermediate signal, located in the rear of signal 8L, by connecting back contact *d* of relay 8TP to back contact *f* of relay 8H, as shown by a dotted line in Fig. 1C.

It will be seen therefore that the directional stick relays, such as relay 6LS and 8LS, are energized when the code operation of the associated track relay ceases due to a train entering the corresponding track section, but are not energized if the code operation of the track relay ceases when the section is not occupied as manifested by the steady energization of the track relay.

One advantage of this arrangement is that it allows all of the opposing signals in the block to assume the stop position in case a train overruns the entering head block signal at the exit end of the block.

This will be clear from the foregoing description since the effect of a train overrunning signal 2RA when signals 6L, 8L, and 4LA are at clear is to open contact *b* of relay 1TP, thereby releasing relay 2RAF and thereby terminating the code operation of relay 2RCT with a period of steady energization, the same as when contact *b* of relay 2RFS is opened by the operator as above described.

It may be that some of the coded track sections are too long for reliable track circuit operation, in which case the track circuit is divided into two sections by insulated joints and the cut section apparatus of Fig. 2 or 3 is interposed as already mentioned.

In Fig. 2 the track relay LTR or RTR for each section when energized supplies current to the rails of the other section, as will be obvious from the drawing. The length of block to which this form of repeater is applicable is limited by the code distortion which may occur due to variations in ballast resistance with weather conditions, the "on" periods of the code tending to be prolonged when the track relays are over-energized, and to be shortened when they are under-energized. This may be compensated for to a large extent and the permissible length of block further increased by "back contact coding," as illustrated in Fig. 3, in which the transmitting relays LCT and RCT are energized over back contacts of the controlling track relays, like relay 6TP in Fig. 1B. In order to obtain equivalent protection in the event of a broken down insulated joint, the plus terminals are connected to the same rail of the adjoining sections in Fig. 2, and to the opposite rails in Fig. 3. Thus Fig. 2 as shown may be interposed between Figs. 1B and 1C, but requires the plus terminals to be connected to the lower rail when interposed between Figs. 1A and 1B or between Figs. 1C and 1D. Fig. 3, on the other hand, when interposed between Figs. 1B and 1C is correctly polarized with respect to Fig. 1B, but requires a reversal of connections of both

sections in Fig. 1C, which in turn requires a reversal of the connections to the rails of the left-hand section in Fig. 1D.

It is to be noted that the apparatus of Fig. 3 repeats the coded current received from either section into the other section with a reversal of phase, each "on" period being repeated as an "off" period, and vice versa. In Fig. 3, if relay LTR remains released when the reception of coded current from the rails of the left-hand section ceases, it is obvious that relay RCT will be held energized to supply current steadily to the rails of the right-hand section, for the release period of relay LTF. The cut section apparatus of Fig. 3 therefore constitutes an alternative means for preventing the energization of the directional stick relays and when this is used, the apparatus at the signal locations for that purpose as hereinbefore described is not needed, and in fact, if used, its effect would be nullified by the phase reversal due to the apparatus of Fig. 3.

It follows therefore that if Fig. 3 is interposed between Figs. 1B and 1C, the branch circuit for relay 6RCT including back contact *c* of relay 6TP and back contact *e* of relay 8H should be omitted so that when relay 8H releases the code operation of relay 6RCT terminates without a period of steady energization. Consequently, in Fig. 3, relay LCT remains released and holds relay RCT picked up to maintain relay 8LTR energized until relays 8H and 8HP release.

When Fig. 3 is interposed between Figs. 1A and 1B, relays 2RAF and 2RAFP may be omitted. The alternative circuit for relay 2RCT for use under this condition may be shown by placing the connector *X* in its upper position, in which the contacts *a* of relays 2RAF and 2RAFP are removed from the circuit so that relay 2RCT will remain released following the opening of contact *b* of relay 1TP or 2RFS.

This alternative circuit is also used when the single track block contains no intermediate signals, as illustrated by placing Fig. 1D directly at the right of Fig. 1A.

It will be understood that when a block section is of sufficient length to require two sets of the cut section apparatus of Fig. 3, the reversal of the phase of the coded current produced by the first set is nullified by the second set, and the alternative arrangements mentioned are not used.

The circuits of my invention also include special provisions for the control of an outlying hand throw switch *W*, as shown in Fig. 4. It will be assumed that switch *W* is located in the intermediate section of the block and that Fig. 4 is interposed between Figs. 1B and 1C.

Fig. 4 includes a set of cut section apparatus by means of which a short releasing section *T*, having a normally energized track relay *TR*, is interposed between two sections of the coded track circuit system.

The operating mechanism for switch *W* is equipped with an electric lock, which may be of the type shown in Letters Patent of the United States No. 1,126,834, issued February 2, 1915, to Neubert et al., for Electric Switch Locks. This serves to lock the operating lever *8* for the switch in its normal position by a latch attached to a segment *25* and held in locking position by the bail *50* of a padlock, and also by a locking dog *27* attached to the armature of a lock magnet *WLM*. The locked condition of switch *W* in its normal position is made manifest in the circuits for signals 6R and 8L which govern traffic move-

ments over the switch by the provision of an indication relay NWP. This relay is normally energized over a circuit which includes the normally closed contact of a push button PB, a contact 26 which is closed when the locking dog 27 is in a position to engage segment 25, and a contact N closed by switch W when locked in its normal position. When the track relay LTR is responding to code, its operation is repeated by relay RCT, the circuit for which extends from terminal B at front contact *a* of relay TR over front contacts *a* of relays LTR and NWP through relay RCT to terminal C. Relay LCT is controlled over front contact *a* of relay RTR by a similar circuit including front contacts *b* of relays TR and NWP.

It will be seen that the transmitter relays RCT and LCT in Fig. 4 repeat the coded currents without change of phase, as in Fig. 2, their circuits differing from those for the transmitter relays of Fig. 3 in this respect.

To unlock switch W for a movement into the side track, the train must occupy section T to release relay TR and the padlock must be removed by the train crew and the segment 25 moved to the position in which it is stopped by the locking dog 27, thereby closing a circuit from terminal B at back contact *a* of relay TR through magnet WLM to terminal C over contacts 46-47. The energization of magnet WLM opens contact 26 to release relay NWP, and lifts the locking dog 27 to permit segment 25 to be moved to full reverse position in which lever 8 is free to be operated to reverse the switch.

For movements out of the side track, cooperation with the central office operator is required, it being necessary for him to reverse the traffic relays 2RFS and 4LFS so as to supply coded current to the track circuit system at both ends.

It will be assumed that the system is already set up for traffic movements from right to left as hereinbefore described, so that the traffic relay 2RFS is reversed and relay 4LFS is normal, with the signal control relay 4LHS in its normal position to hold signals 4LA and 4LB at stop. The reversal of relay 4LFS disables the circuits for signals 4LA and 4LB and sets the transmitter relay 4LCT into operation at the 75 code rate, its circuits being similar to those for relay 2RCT already described. The padlock bail 50 is removed by the train crew and segment 25 is moved to its intermediate position thereby energizing a slow release relay NWPR over contacts 46-47 and a contact *c* of relay NWP. The push button PB is pressed by a member of the train crew, thereby releasing relay NWP, and in turn releasing relay NWPR after a release period during which relay RCT is held steadily energized over the circuit from terminal B at front contact *b* of relay LTR over front contact *a* of relay NWPR and back contact *d* of relay NWP. Relay RCT then releases, but relay LTR continues to operate and the closing of back contact *a* of relay NWP causes the slow release relay LTF to become energized, its circuit extending from terminal B over front contacts *a* of relays TR and LTR and back contact *a* of relay NWP through relay LTF to terminal C, and the slow release relay LTB is energized over the back contact *a* of relay LTR and the front contacts *a* of relay LTF and TR.

If relay 4LFS is reversed by the operator before relay NWP is released by the train crew, relay 8RCT of Fig. 1C and relay 4LCT of Fig. 1D will both be in operation for a time, at dif-

ferent rates, and current will be supplied over the track rails by relay 4LCT to pick up relay 8RTR at irregular intervals whenever relay 8RCT releases and relay 4LCT is picked up. The slow release relay 8RTF will therefore become energized, and since relay 8LTF is also energized, relay 8TP will remain released, de-energizing relay 8TP, transformer 8DT and mechanism 8LG, and releasing relays 8H and 8HP without operating the directional stick relay 8LS. The release of relay 8H and mechanism 8LG stops the code operation of relay 8RCT, which relay then remains released and allows relay 8RTR to respond properly to the code transmitted by relay 4LCT. Signal 8R, however, is held at stop and relay 8LTR is prevented from operating until relay 8LTR ceases to operate and thereby releases relay 8LTF.

If on the other hand, relay NWP is released by the train crew before the operator reverses relay 4LFS, relay 8LTR ceases to operate and releases relays 8H and 8HP and restores signal 8L to stop without energizing relay 8LS, due to the period of steady energization of relay 8LTR provided by relay NWPR as above described.

In either case, the code operation of relay 8RTR, due to the reversal of relay 4LFS, together with the release of relay 8LTF, due to the release of relay NWP, conditions signal 8R to indicate caution and to operate relay 8LTR at the 180 code rate to which relay RTR of Fig. 4 responds and thereby energizes the slow release relays RTF and RTB over circuits similar to those traced above for relays LTF and LTB. When relays RTB and LTB are both energized, a circuit is closed over their contacts *a* to energize magnet WLP to unlock the switch.

It will be understood that after the train entering the block via switch W occupies the main track and has fully passed the switch, switch W is restored to normal and locked in that position to energize relay NWP, and the central office operator will restore relay 4LFS to normal when he has been advised by the train crew that this has been done.

In the foregoing it has been assumed that the energization of relay LTB to unlock the switch is due to the operation of relay LTR at the 180 code rate, indicating that the entire portion of the block at the left of switch W is vacant. Relay LTB may also be energized by the operation of relay LTR at the 75 code rate, indicating that the block is occupied by a train beyond signal 6L moving away from the switch. Switch W may therefore be reversed to permit a train to follow another train through the block as soon as the first train is entirely past the first signal beyond the switch. Likewise, signal 4LA or 4LB may be cleared under similar conditions, provided relay NWP has been reenergized.

In the foregoing, the operation of the apparatus has been considered principally with reference to traffic movements from right to left, with the track switches 1W and 3W in their normal positions. Since the circuits for the two directions are similar, it is deemed unnecessary to describe their operation in detail, for traffic movements from left to right, nor to describe the operation involving the clearing of signals 2RB and 4LB for movements out of the passing tracks, the circuits for which are similar to those for signal 4LA as described in detail herein.

Although I have herein shown and described

only one form of railway traffic controlling apparatus embodying my invention together with several modifications of portions thereof as applied to different situations, it is understood that various changes and modifications may be made therein within the scope of the appended claims without departing from the spirit and scope of my invention.

Having thus described my invention, what I claim is:

1. In combination, a stretch of single track railway comprising two adjoining track sections, a track relay for one section connected across the rails of its section, a directional stick relay, a code detector relay selectively responsive to the periodic operation of said track relay, a slow release repeating relay for said code detector relay, means at the remote end of said one section for supplying periodically interrupted current to the track rails thereof to operate said track relay to indicate the unoccupied condition of said one section, a pick-up circuit for said directional stick relay including a back contact of said code detector relay and a contact which closes each time the track relay is released, said circuit also including a front contact of said repeating relay, a stick circuit for said directional stick relay including its own front contact and a back contact of said code detector relay, and means controlled by said directional stick relay when energized for supplying periodically interrupted current to the rails of the other of said adjoining track sections.

2. In combination, a stretch of single track railway comprising two adjoining track sections, a track relay for one section connected across the rails of its section, a directional stick relay, a code detector relay selectively responsive to the periodic operation of said track relay, a slow release repeating relay for said code detector relay, means at the remote end of said one section for supplying periodically interrupted current to the track rails thereof to operate said track relay to indicate the unoccupied condition of said one section, a pick-up circuit for said directional stick relay including a back contact of said code detector relay and a contact which closes each time the track relay is released, said circuit also including a front contact of said repeating relay, a stick circuit for said directional stick relay including its own front contact and a back contact of said code detector relay, means acting whenever the supply of periodically interrupted current to the rails of said one section is discontinued for supplying steady current to said rails for a time sufficient to effect the release of the code detector relay and of its repeating relay while the track relay is held energized to prevent the closing of the pick-up circuit for said directional stick relay, and means controlled by said directional stick relay when energized for supplying periodically interrupted current to the track rails of the other of said adjoining track sections.

3. In combination, a stretch of single track railway comprising two adjoining track sections, a code following track relay connected across the rails of one of said sections, means at the remote end of said one section for supplying coded current to the track rails thereof to operate said track relay, a code detector relay which assumes its energized position in response to the code operation of said track relay, a slow release repeating relay controlled by a front contact of said code detector relay, a directional stick relay, a pick-up circuit for said directional stick relay including a front contact of said repeating relay and a contact which closes each time the track

75

relay releases and arranged to be completed only when said code detector relay is released by the continued deenergization of said track relay, a stick circuit arranged to hold said directional stick relay energized until said code detector relay is again energized, and means controlled by said directional stick relay when energized for supplying coded current to the rails of the other of said adjoining track sections.

4. In combination, a stretch of single track railway comprising two adjoining track sections, a code following track relay connected across the rails of one of said sections, means at the remote end of said one section for supplying coded current to the track rails thereof to operate said track relay, a code detector relay which assumes its energized position in response to the code operation of said track relay, a slow release repeating relay controlled by a front contact of said code detector relay, a directional stick relay, a pick-up circuit for said directional stick relay including a front contact of said repeating relay and a contact which closes each time the track relay releases and arranged to be completed only when said code detector relay is released by the continued deenergization of said track relay, a stick circuit arranged to hold said directional stick relay energized until said code detector relay is again energized, means effective whenever the supply of coded current to the rails of said one section is discontinued for supplying steady current thereto to hold the track relay energized for a time sufficient to cause said code detector relay and its repeating relay to release before said track relay is released, whereby said directional stick relay is caused to be energized when the track relay remains released due to a train entering said one section but not if the code operation of said track relay ceases while said one section is unoccupied, and means controlled by said directional stick relay when energized for supplying coded current to the track rails of the other of said adjoining track sections.

5. In combination, a stretch of single track railway comprising two adjoining track sections, a code following track relay connected across the rails of one of said sections, means at the remote end of said one section for supplying coded current to the track rails thereof to operate said track relay, a code detector relay which assumes its energized position in response to the code operation of said track relay, a slow release repeating relay controlled by a front contact of said code detector relay, a directional stick relay, a pick-up circuit for said directional stick relay including a front contact of said repeating relay and a contact which closes each time the track relay releases and arranged to be completed only when said code detector relay is released by the continued deenergization of said track relay, a stick circuit arranged to hold said directional stick relay energized until said code detector relay is again energized, means controlled by said directional stick relay when energized for supplying coded current to the rails of said other track section, and means for rendering the energization of said directional stick relay dependent upon whether the release of said code detector relay is due to a train entering said one section or is due to the termination of the supply of coded current to the rails thereof, comprising means for supplying steady current to the rails of said one section following the termination of the supply of coded current for a time sufficient to release said code detector relay and its repeating relay before said track relay is released.

6. In combination, a stretch of railway track divided into track sections, means effective only when the end section of said stretch is unoccupied for supplying coded current to the track rails of a second section adjoining said end section, a code following track relay at the remote end of the second section responsive to said coded current, a directional stick relay associated with said track relay effective when energized to supply coded current to the track rails of a third section adjoining said second section, a code detector relay which assumes its energized position in response to the continued code operation of said track relay, a slow release repeating relay controlled by front contacts of said code detector relay, a pick-up circuit for the directional stick relay including a contact closed when the track relay releases and a front contact of said repeating relay and adapted to be closed in response to the release of said code detector relay when the code operation of said track relay ceases due to the movement of a train from the third section to the second section, a stick circuit for maintaining said directional stick relay energized until said code detector relay is again energized, and means for preventing the energization of said directional stick relay when the code operation of said track relay ceases due to the occupancy of said end section by an opposing train, comprising means rendered effective when the supply of coded current to the rails of the second section is terminated by the occupancy of said end section for supplying steady current to the rails of said second section to hold the track relay energized until the code detector relay and its repeating relay are released.

7. In combination, a stretch of railway track divided into track sections, means effective only when the end section of said stretch is unoccupied for supplying coded current to the track rails of a second section adjoining said end section, a code following track relay at the remote end of the second section responsive to said coded current, a directional stick relay associated with said track relay effective when energized to supply coded current to the track rails of a third section adjoining said second section, a code detector relay which assumes its energized position in response to the continued code operation of said track relay, a slow release repeating relay controlled by front contacts of said code detector relay, a pick-up circuit for the directional stick relay including a contact closed when the track relay releases, a back contact of said code detector relay and a front contact of said repeating relay and adapted to be closed momentarily in response to the release of said code detector relay, provided the track relay remains in its released position when the code operation of said track relay ceases, and means rendering the energization of said directional relay dependent upon whether said code detector relay is released due to a train entering said second section from said third section or is due to an opposing train entering said end section, comprising means controlled by a train entering said end section for supplying steady current to the track rails of said second section to terminate the code operation of the track relay by holding such relay steadily energized until the code detector relay and its repeating relay have released.

8. In combination, a stretch of single track railway divided into reversible track sections

each having a track relay at each end, signals at the ends of said sections for governing traffic movements through said stretch in opposite directions, a code detector relay for each signal for controlling the signal, means for selectively energizing each code detector relay in response to the operation of an adjacent track relay by periodically interrupted current in the rails of the section in advance of the corresponding signal, a manually controllable traffic relay at each end of the stretch, means controlled by said traffic relays and by the code detector relays for the intermediate signals in said stretch for supplying periodically interrupted current to the track rails of the sections to energize said track relays in cascade by periodically interrupted current as required to establish either direction for traffic movements through the stretch, a directional stick relay for each intermediate signal, a pick-up circuit for each directional stick relay closed when the reception of current over the track rails at the location thereof ceases and the code detector relay for the associated signal is released, due to the continued deenergization of the associated track relay, a stick circuit for holding each directional stick relay picked up until the associated code detector relay is again energized, means controlled by each directional stick relay when energized for supplying periodically interrupted current to the track rails for the track section in the rear of the signal with which such stick relay is associated, means associated with each directional relay for preventing its energization in response to the release of the code detector relay for the associated signal due to the continued energization of the associated track relay by steady current supplied over the track rails in advance of such signal, and means at each end of the stretch for temporarily supplying steady current to the track rails of said sections in cascade whenever the supply of interrupted current to the track rails at that end is discontinued, for a time sufficient to effect the release of said code detector relays without energizing any of said directional relays.

9. In combination, a stretch of single track railway comprising two adjoining track sections, a code following track relay for each section connected across the track rails thereof, means at the remote end of each section for supplying coded current to the track rails to operate the track relay for that section, a slow release repeating relay for each track relay, a code detector relay which assumes its energized position in response to the code operation of either track relay, a slow release repeating relay controlled by a front contact of said code detector relay, a directional stick relay for each track relay, a pick-up circuit for each directional stick relay including a back contact of the other directional relay, front contacts of the repeating relays for the associated track relay and for said code detector relay and arranged to be closed when said code detector relay releases in response to the steady deenergization of said track relay, a stick circuit arranged to hold the energized directional stick relay picked up until said code detector relay is again energized, means controlled by each directional stick relay when energized for supplying coded current to the rails of the other section, and means for rendering the energization of each directional stick relay dependent upon whether or not the release of the code detector relay is due to the occupancy of the corresponding track section, comprising means at

the remote end of each section acting whenever the supply of coded current to the track rails thereof is discontinued for supplying steady current to said rails to hold the corresponding track relay energized for a time sufficient to release said code detector relay and its repeating relay.

10. In combination, a stretch of single track railway comprising two adjoining track sections, code following track relays connected across the rails of said sections, that for one section being located at the junction of said sections and that for the other section at the remote end of such section, means at the remote end of said one section for supplying coded current to the rails thereof to operate the track relay thereof, a code detector relay which assumes its energized position in response to the code operation of the track relay for said one section, a slow release repeating relay for said code detector relay, a directional stick relay, a pick-up circuit for said directional stick relay including a front contact of said repeating relay and arranged to be closed if said code detector relay releases while said track relay occupies its released position, a stick circuit arranged to hold said directional stick relay energized until said code detector relay is again energized, means effective when said code detector relay is energized for supplying current coded at a given rate and when said directional stick relay is energized for supplying current coded at a different rate, to the track rails of said other section, means for rendering the energization of said directional stick relay dependent upon whether the release of said code detector relay is due to a train entering said one section or is due to the termination of the supply of coded current to the rails thereof, comprising means for supplying steady current to the rails of said one section following the termination of the supply of coded current for a time sufficient to release said code detector relay and its repeating relay before the track relay for said one section is released, and means rendered effective upon the release of said code detector relay while the track relay for said one section is energized for supplying steady current to the track rails of the other section as long as said track relay remains energized.

11. In combination, a stretch of single track railway divided into track sections, signals at the ends of said sections for governing traffic movements in both directions, each such signal being arranged to indicate stop except when the track section in advance is supplied with periodically interrupted current, a directional stick relay for each intermediate signal in said stretch, manually controllable means for supplying periodically interrupted current to the track rails at one end of the stretch or the other to designate the direction for traffic movement in the stretch, code detector means at each signal location selectively responsive to periodically interrupted current received over the track rails from either track section for supplying current periodically interrupted at a given rate to the track rails of the other sec-

tion at that location, whereby said track sections are energized in cascade when the stretch is unoccupied, means for energizing each directional stick relay in response to the release of the associated code detector means when current ceases to be received over the track rails at that location, means for maintaining such relay energized until such code detector means again indicates the reception of periodically interrupted current, means for rendering the energization of each directional stick relay dependent upon whether or not the corresponding track section is occupied comprising means for supplying steady current to the rails of said section to which such relay is non-responsive for a time following the termination of the supply of interrupted current thereto, sufficient to effect the release of said code detector means without energizing said relay, means controlled by each directional stick relay for supplying current to the rails of the adjoining track section interrupted at a rate different from that supplied thereto when the associated code detector means is energized, and means responsive to periodically interrupted current in the track rails in advance of a signal for causing such signal to indicate proceed or caution dependent upon the rate of interruption of said current.

12. In combination, a stretch of single track railway divided into track sections, a traffic relay at each end of the stretch, means controlled by each traffic relay when operated for supplying periodically interrupted current to the track rails for establishing the direction for traffic movements through the stretch, a directional stick relay for each direction at each junction of two sections in said stretch, a pick-up circuit for each directional stick relay including a back contact of the other directional stick relay at the same location and arranged to be closed when periodically interrupted current ceases to be received over the track rails at that location from the corresponding direction, provided the reception of such current is terminated by a prolonged interval during which no current is received, a stick circuit for maintaining each energized directional stick relay picked up until interrupted current is again received at its location in the corresponding direction, means effective when the operated traffic relay is restored to normal and the supply of interrupted current is thereby discontinued for supplying steady current to the track rails for a time to prevent the energization of such directional stick relays, means at each junction of two sections for supplying periodically interrupted or steady current to the rails of either section as long as such current is being received over the track rails of the other section at that location, and means controlled by the directional stick relay for either section when energized for supplying periodically interrupted current to the track rails of the other section at the same location.

CHARLES B. SHIELDS.
